UNITED STATES PATENT OFFICE

GILBERT J. HAAN, OF GRAND RAPIDS, MICHIGAN, ASSIGNOR TO KEELER BRASS COMPANY, OF GRAND RAPIDS, MICHIGAN

DOOR HANDLE

Application filed May 15, 1930. Serial No. 452,565.

The main object of this invention is to provide a handle which is particularly well adapted for safes, cabinets and the like, which may be formed mainly of sheet metal, is strong and rigid, and has a substantial appearance.

Objects pertaining to details and economies of my invention will definitely appear from the description to follow. The invention is defined in the claims.

A structure which embodies the features of my invention is clearly illustrated in the accompanying drawing, in which:

Fig. 1 is a side view of a handle embodying the features of my invention.

Fig. 2 is a front elevation thereof, the grip being partially broken away.

Fig. 3 is a fragmentary view mainly in central section on a line corresponding to line 3-3 of Fig. 2.

Fig. 4 is a transverse section through the grip or handpiece on line 4-4 of Figs. 1 and 2.

Fig. 5 is a perspective view of the safe parts disassembled.

Reference being had to the accompanying drawing, 1 is the escutcheon member having a raised portion 2 with an opening therein. 3 represents the spindle of the latch. This spindle is slotted at 4 to receive the bolt 5. The tubular shank 6 is arranged through the opening in the escutcheon plate and arranged to receive the end of the spindle 3, the spindle being locked to the shank when the bolt is projected as shown in Fig. 3.

The locking unit designated generally by the numeral 7 is arranged within the tubular shank to coact with the bolt. The details of this locking unit do not constitute a part of this invention and are not described.

The shank is embraced by a finishing sleeve 8 preferably drawn or formed from sheet metal. The inner end of this sleeve abuts the escutcheon plate and has an inturned flange 9 fitting the shank to center the sleeve and also to provide a rounded finish for its inner end.

The grip or handpiece 10 is also formed of sheet metal conformed to a tubular tapered form as shown and having an integral

collar 11 at its inner end arranged upon the shank 6 and fixedly secured thereto, preferably by spot welding as at 12. The inner end of this collar 11 is flared outwardly at 13 to embrace the outer end of the sleeve.

The handpiece has an outturned flange 14 at its outer end with which the flanged cap plate 15 is engaged.

A thimble-like finishing cap piece 16 is arranged to embrace the collar portion of the handpiece with its inner edge turned inwardly at 17 to engage the inner edge of the handpiece collar 11. The outer end of this cap piece 16 has an inturned flange 18 projecting into the sleeve and abutting the end of the shank. The flange is turned inwardly at 19 providing a seat for the shoulder 20 on the locking unit 7. The cap piece 16 has a collar portion 21 folded around the handpiece adjacent its collar, see Fig. 3.

The parts are thus very securely retained in assembled relation, are mainly formed of sheet metal, and at the same time are strong and rigid with a substantial appearance.

I have illustrated and described my improvements in a very practical embodiment especially designed for lockers, office cabinets and the like. My improvements are, however, desirable for use in numerous other relations.

Having thus described my invention what I claim as new and desire to secure by Letters Patent is:

1. In a handle, the combination of an escutcheon member, a tubular shank projecting into said escutcheon member, a sleeve arranged on said shank in abutting relation to said escutcheon member, a handpiece formed of sheet metal having an integral collar arranged on the outer end of said shank and spot welded thereto, the inner edge of said collar being flared to embrace the end of said sleeve, and a thimble-like cap piece embracing said collar portion of said handpiece and having a tubular collar portion folded around and embracing the inner end of said handpiece, the inner edge of said cap piece being folded under the inner edge of said collar, said cap piece having an inturned

- flange projecting into said collar and abutting the end of said shank.
2. In a handle, the combination of a shank, a sleeve arranged on said shank, a handpiece formed of sheet metal having an integral collar arranged on the outer end of said shank and spot welded thereto, the inner edge of said collar embracing the end of said sleeve, and a thimble-like cap piece embracing said collar portion of said handpiece and having a tubular collar portion folded around and embracing the inner end of said handpiece, the inner edge of said cap piece being folded under the inner edge of said collar, said cap piece having an inturned flange projecting into said collar and abutting the end of said shank.
3. In a handle, the combination of an escutcheon member, a tubular shank projecting into said escutcheon member, a sleeve arranged on said shank in abutting relation to said escutcheon member, a handpiece formed of sheet metal having an integral collar arranged on the outer end of said shank and spot welded thereto, the inner edge of said collar being flared to embrace the end of said sleeve, and a thimble-like cap piece embracing said collar portion folded around and embracing the inner end of said handpiece.
4. In a handle, the combination of a shank, a sleeve arranged on said shank, a handpiece formed of sheet metal having an integral collar arranged on the outer end of said shank and spot welded thereto, the inner edge of said collar embracing the end of said sleeve, and a thimble-like cap piece embracing said collar portion of said handpiece and having a tubular collar portion folded around and embracing the inner end of said handpiece.
5. In a handle, the combination of a tubular shank, a sleeve arranged on said shank, a handpiece having an integral collar portion arranged on the outer end of said shank and secured thereto, the inner edge of said collar embracing the end of said sleeve, and a cap piece embracing said collar and having a collar portion embracing the inner end of said handpiece, the edge of said cap piece being in engagement with the inner edge of said handpiece collar, said cap piece having an inturned flange at its outer end projecting into said collar.
6. In a handle, the combination of a shank, a sleeve arranged on said shank, a handpiece having an integral collar portion arranged on the outer end of said shank and secured thereto, the inner edge of said collar embracing the end of said sleeve, and a cap piece embracing said collar and having a collar portion embracing the inner end of said handpiece, the edge of said cap piece being in engagement with the inner edge of said handpiece collar.
7. In a handle, the combination of a shank,

a handpiece having an integral collar portion arranged on the outer end of said shank and secured thereto, and a cap piece embracing said collar and having a collar portion embracing the inner end of said handpiece, the edge of said cap piece being in engagement with the inner edge of said handpiece collar, said cap piece having an inturned flange at its outer end projecting into said collar.

8. In a handle, the combination of a shank, a handpiece having an integral collar portion arranged on the outer end of said shank and secured thereto, and a cap piece embracing said collar and having a collar portion embracing the inner end of said handpiece, the edge of said cap piece being in engagement with the inner edge of said handpiece collar.

9. In a handle, the combination of a shank, a handpiece having an integral collar portion arranged on the outer end of said shank and secured thereto, and a cap piece embracing said collar and having a collar portion embracing the inner end of said handpiece, said cap piece having an inturned flange at its outer end projecting into said collar.

10. In a handle, the combination of a shank, a handpiece having an integral collar portion arranged on the outer end of said shank and secured thereto, and a cap piece embracing said collar and having a collar portion embracing the inner end of said handpiece.

In witness whereof I have hereunto set my hand.

GILBERT J. HAAN.
